UNITED STATES PATENT OFFICE.

ROBERT PORTER WISE, OF TULSA, OKLAHOMA.

HEATING APPARATUS.

Application filed September 25, 1920. Serial No. 412,886.

To all whom it may concern:

Be it known that I, ROBERT PORTER WISE, a citizen of the United States, residing at Tulsa, in the county of Tulsa and State of 5 Oklahoma, have invented certain new and useful Improvements in Heating Apparatus, of which the following is a specification.

This invention relates to heating apparatus and has for an object the production of 10 a machine which will render the adhesive constituent of an elastic canvas, used for insoles of shoes, etc., soluble to permit expeditious application of the canvas to the insole.

It is desirable in this art to apply canvas 15 strips to insoles of shoes, etc., for reinforcing insoles, thereby reducing possibility of the shoe upper becoming disengaged. With this end in view I have designed the present invention to expedite the present methods of 20 heating the canvas and to insure thorough heating of the same, thereby causing uniform adhesion of the canvas to the insole.

The above and other objects of this invention will be in part described and in part 25 understood from the following description of the present preferred embodiment of the invention taken in connection with the accompanying drawings, wherein:

Fig. 1, is a side elevational view of a device constructed in accordance with my invention.

Fig. 2, is a horizontal sectional view taken on the line 2—2 of Fig. 1, and looking in the direction of the arrow.

Fig. 3, is a vertical sectional view of the device showing parts thereof broken away and showing to advantage the manner of introducing steam into the heating casings.

Fig. 4, is a fragmentary longitudinal sectional view of the casings, and

Fig. 5, is a fragmentary sectional view taken on the line 5—5 of Fig. 4 and looking in the direction of the arrow.

The device of my invention consists of a 45 supporting structure generally designated 6, which is formed from a plurality of vertical legs, the upper ends of which are secured in pockets 7 carried by a heating casing hereinafter described. Bracing struts 8 are pro-

vided, one of which engages a diagonally arranged pocket 9, while the opposite end extends into and is pivotally engaged with one of the vertical legs. The other strut member has one end pivotally engaged with the 55 first said strut member and the opposite end pivotally engaged with the other supporting

leg on the side upon which said struts are mounted. It is to be understood that the supporting structure is the same on both sides of this device, consequently only one 60 side has been above described.

Upper and lower heating casings 10 and 11 respectively are provided, both of which consists of tubular steam receiving members. The lower casing 11 is preferably of an oblong configuration and consists of an inner 65 metallic housing 12, which is encased on its bottom face and both sides with a sheet of asbestos 13 or other suitable insulating material. An outer shell 14 is mounted over 70 the asbestos sheet and has its upper face contiguous with the upper face of the inner housing 12. As shown to advantage in Fig. 1, one end of said lower casing is bent downwardly as indicated at 15. Said downwardly 75 curved end is engaged by the rear legs of the supporting structure. Each end of the casing 11 has detachably mounted thereon a covering 16, which is likewise preferably made of metal. The upper casing also 80 consists of an inner housing, as indicated at 16, an outer shell 17, and an asbestos sheet 18, which extends between the top faces and sides of said inner housing and outer shell. The upper casing terminates short of the 85 opposite ends of the lower casing and is spaced therefrom by means of longitudinally extending ribs 19. It will be observed that the ribs 19 extend the entire length of the lower casing and are secured to the upper face of 90 the latter, thereby providing runways for a purpose hereinafter described.

A steam pipe 20 extends upwardly along one side of the casings 10 and 11 and is equipped with lateral tributaries 21, which 95 have formed therein perforations so that the steam may be emitted in jets in the casings. A valve 22 is mounted in the pipe 20 for controlling the influx of steam into said tributaries. A second valve 23 is provided 100 which is arranged between the two tributaries, so that steam may be permitted to flow into the lower casing only if desired. On the other hand, when it is desired to permit the steam to pass into both 105 casings, both the valves 22 and 23 will be opened. An exhaust pipe 24 is provided which is connected with the rear end of the upper casing 10 and communicates with the latter. A tributary 25 extends laterally from 110 said exhaust pipe and communicates with the lower casing through the side of the

latter. The exhaust steam can be conducted independently from the lower casing 11, if desired, or may be conducted simultaneously from both casings in view of valves 26, 5 used in an obvious manner.

A supporting structure for carrying canvas rolls is mounted on the rear legs of the device and consists of supporting brackets 27, which have mounted therein a roller 10 28. This roller carries a plurality of rolls of canvas 29, the number of canvas rolls conforming to the number of runways provided on the lower casing. In the present instance, 15 four runways have been provided, consequently, four rolls of canvas are shown. It is to be understood, however, that if desired, only one roll of canvas may be used, and on the other hand, a greater number than four may be used, without departing from the 20 scope of the invention.

In use of this device, the free ends of the canvas rolls are mounted upon the runways provided between the ribs 19 and are operated over said runways in any desired manner. 25 Steam is introduced into either or both of the upper and lower casings by proper manipulation of the valves 22 and 23. In passing between these casings the canvas will be thoroughly heated, so as to render 30 the adhesive constituent of elastic canvas, tacky. The insoles are engaged with the canvas at the outlet end of the lower casing. By providing the ribs 19, it will be obvious that the canvas strips will be held 35 separated, preventing them from adhering. Moreover, by bending the rear end of the lower casing downwardly, the latter will be in convenient proximity to the canvas rolls, permitting the canvas to move uninterrupted 40 over the arcuate face of the lower casing. Moreover, by introducing the steam into the casings adjacent the outer ends of the latter, and permitting the steam to exhaust at the opposite ends of the casings,

it will be apparent that the maximum heat 45 applied to the canvas will be at all times applied to the canvas as it is about to leave the casings. Consequently, the canvas will by this process be thoroughly heated to insure uniform adhesion of the canvas to the 50 insole. Upon reference to Fig. 5 of the drawings, it will be noted that the inner housing of each casing is provided with a right angled flange 30, which receives the screw threaded ends of the bolt used for 55 securing the cover 16 thereto, these bolts also serving to clamp the asbestos and hold it from displacement.

It is to be understood that the arrangement of supporting structure, manner of connection of the same to the casings, form of steam valves, etc., may be changed if desired, in conformity with the conditions under which the device of my invention will operate. The structure herein shown is merely illustrative of the principle of my invention and I do not wish to be limited thereby.

What is claimed is:

A heating apparatus including superposed heating casings the ends of one of which 70 fall short of the ends of the other, ribs arranged between said casings and extending the full length of the longer casing to provide independent channels, a support for canvas rolls supported adjacent said longer 75 casing to feed a length of canvas in each channel, steam inlet pipes each of which is equipped with a lateral perforate extension, said extensions projecting into the casings and extending transversely thereacross to 80 emit the steam in jets.

In testimony whereof I affix my signature in presence of two witnesses.

ROBERT PORTER WISE.
